UNITED STATES PATENT OFFICE

153,441

DESIGN FOR A DUST CAP FOR TIRE VALVE STEMS

Amos H. Marchus, Oakland, Calif.

Application October 21, 1946, Serial No. 134,137

Term of patent 14 years

(Cl. D90—20)

To all whom it may concern:

Be it known that I, Amos H. Marchus, a citizen of the United States and a resident of the city of Oakland, county of Alameda, State of California, have invented a new, original, and ornamental Design for a Dust Cap for Tire Valve Stems, of which the following is a specification, reference being had to the accompanying drawings, forming a part thereof.

Figure 1 is a top plan view of a dust cap for tire valve stems, showing my new design;

Figure 2 is a side elevational view thereof;

Figure 3 is a fragmentary sectional elevational view thereof;

Figure 4 is a bottom perspective view thereof; and

Figure 5 is a bottom plan view thereof looking directly into the interior.

I claim:

The ornamental design for a dust cap for tire valve stems as shown.

AMOS H. MARCHUS.
